ATTORNEY

UNITED STATES PATENT OFFICE.

CELINDA P. ROBINSON, OF NEW YORK, N. Y.

FURNITURE-PAD.

SPECIFICATION forming part of Letters Patent No. 660,064, dated October 16, 1900.

Application filed February 8, 1899. Serial No. 704,999. (No model.)

To all whom it may concern:

Be it known that I, CELINDA P. ROBINSON, a citizen of the United States, residing at New York city, in the county of New York and State of New York, have invented certain new and useful Improvements in Furniture-Pads; and I do hereby declare the following to be a full, clear, and exact description of the invention, such as will enable others skilled in the art to which it appertains to make and use the same.

This invention relates to cushions or pads adapted for use upon articles of furniture for the purpose of cushioning and preventing injury from violent contact with the floor, walls, adjacent furniture, &c.; and this invention has for its objects the provision of an automatic pneumatic cushion and the effective inclosure of the fastening devices and various other objects, as will appear from the following description of pads embodying my invention, referring to the accompanying drawings, forming part hereof.

Figure 1 is a side elevation of a rocking-chair having pads thereon embodying my invention. Fig. 2 is an enlarged detail, partly in section, of the rear end of a rocker with the pad thereon. Fig. 3 is an elevation of the same. Fig. 4 is a sectional elevation showing a modified form of pad. Fig. 5 is an elevation of another modified form of pad.

An ordinary rocking-chair A is shown in Fig. 1, having a rocker A' and a back A², and this rocking-chair is shown as provided with pads B, embodying my invention on the rocker thereof and on the back thereof. Each of these pads contains or is made of rubber or other flexible and elastic material which will yield to pressure and when relieved of the pressure will spring back to its normal shape. This pad is provided with a knob or rounded protruding part B² and is formed with an interior air-recess B³ and an orifice or vent B⁴, located in a striking-face thereof and leading into the recess B³. This vent B⁴ normally permits free entrance and escape of air; but when the knob collides with any object the object collided with acts as a valve to partially close the vent, the pressure with which it acts depending upon the force of the blow, and the air-restraining power of the vent being therefore automatic or self-adjusting and adjust-

ing itself to the force of the blow. I prefer to locate this vent B⁴ so that it will be forced against an object in the event of a direct blow against the pad, as this character of blow is usually the most forceful and would, if not cushioned, be most destructive, and the vent is shown as thus located in the constructions shown in Figs. 1 to 3 and Fig. 5; but in some instances I may locate the vent in the side of the knob or rounded protruding part, so that the vent will be partially closed and the automatic pneumatic action be brought about by a side blow.

According to my invention the pad is secured to the article by a fastening device entered through the vent, and the pad has a suitable base B⁵, adapted to bear against the article to which it is attached, and this fastening device is shown in Fig. 2 as a screw N and washer N'. The elasticity and pliability of the material of the pad permits the fastening device to be entered through a vent much smaller than the fastening device, and in the construction shown the screw N and washer N' can be readily entered through the small vent B⁴ by slight stretching of the walls of the vent. As a result of this construction the fastening device is concealed within the pad and inclosed by yielding material, so that no hard or metal parts are exposed. A pad provided with a knob embodying my invention may, however, be secured by external fastening devices, as shown in Fig. 5, such pad having an extended base-flange B⁶, held by screws N².

In the modified construction shown in Fig. 4 the pad is shown as provided with a hood B', molded to conform to the shape of the rear A² of the rocker, and provided with an additional vent B⁵, which extends from the interior air-chamber through the hood, so as to permit air to escape when the hood is drawn onto the rocker, thereby preventing accumulated air from causing the hood to work off the rocker.

It will be observed that a double purpose is accomplished by having the pad made of elastic material as well as provided with the recess B³ and vent B⁴, as a yielding envelop is provided for the pneumatic cushion, and at the same time the yielding character of the pad will bring about a cushioning of a

blow in any direction and of a blow of such a nature as not to cause a partial closure of the vent B⁴, and thus the article provided with my improved pad is effectually shielded 5 from causing or receiving injury from any sort of blow or concussion received by the pad.

While I have shown this pad as applied to a rocking-chair, it may be used in many ways 10 and on many articles to prevent injury from 15 blows or concussions. It is of course evident that various modifications may be made in the constructions above described within the purview of my invention.

What I claim, and desire to secure by Letters Patent, is—

1. A pad for cushioning blows, such pad being made of flexible and elastic material and provided with an air-chamber and with 20 a vent extending from said air-chamber to a striking-face of the pad, substantially as set forth.

2. A pad for cushioning blows having a protruding part of flexible material with an air-chamber therein and with a vent extending 25 from said air-chamber to a striking-face of such protruding part, and provided with a base for attachment to the article to be protected, substantially as set forth.

3. A pad for cushioning blows made of flexible and elastic material and having a knob 30 with an air-chamber therein and with a vent extending from said air-chamber to a striking-face of the knob, and provided with a base having a perforation to receive a fasten-

ing device, such perforation extending from 35 said air-chamber to said base, substantially as set forth.

4. The combination with an article of furniture or other article, of a pad for cushioning blows having a compressible knob with 40 an air-chamber therein and with a vent extending from said air-chamber to a striking-face of the knob and provided with a base, and a fastening device extending from said air-chamber through said base to said article, substantially as set forth. 45

5. The combination with an article of furniture or other article, of the pad B having the knob B² with the air-chamber B³ therein and the vent B⁴, such vent B⁴ extending from 50 said air-chamber to the outer face of said knob, and such pad having the base B⁸, and a fastening device adapted to be entered through the vent B⁴ and extending from said base to said article, substantially as set forth. 55

6. The pad for cushioning blows having the knob B² with the air-chamber B³ therein and the vent B⁴, such vent B⁴ extending from said chamber to the outer face of said knob, and such pad having the base B⁸ provided with a 60 perforation therein extending from said air-chamber, substantially as set forth.

In testimony whereof I affix my signature in presence of two witnesses.

CELINDA P. ROBINSON.
